UNITED STATES PATENT OFFICE

MARK ROBINSON, OF WATERLOO, NEAR LIVERPOOL, ENGLAND

STEAM GENERATOR

Application filed November 5, 1926. Serial No. 146,412.

This invention relates to improvements in steam-generators, and more particularly generators of the marine boiler type. The object of the invention is to provide a steam-generator of a compound character which is adapted to suit varying steam supply requirements.

According to my invention, the internal space of a steam-generator enclosed by the boiler-shell is divided into two separate portions, so as to form, in effect, two independent generator units, which are capable of being worked independently of each other, or both together. To this end, the water and steam space enclosed by the boiler-shell of the main boiler is divided by longitudinal partitions and an end or cross partition into two separate and independent generator units. One of these generator units occupies the middle portion of the space enclosed by the boiler shell and the other generator unit comprises the rest of the water and steam space, that is to say, the two wing portions on the sides of the central generator, and the space behind it.

The plating forming the shell of the central generator unit extends from top to bottom of the main boiler shell and is riveted thereto, and this central generator is stayed by stay-bolts to the wing-furnaces, and also in its lower part to the main boiler shell, and further its sides are stayed together by rows of cross stays. In its upper part it is further stayed by the longitudinally extending stay-bolts connecting the two end-plates of the main boiler-shell.

The central generator is heated by the middle furnace and one of the clusters of smoke-tubes in the case of a three furnace boiler, or by the two middle furnaces in the case of a boiler with four furnaces.

The central generator is provided with means for supplying it with feed-water to maintain an operative level therein for the independent generation of steam, and also

with means for delivering the high pressure steam generated in it.

It will thus be seen that I provide a compound steam-generator divided into two independent generator units which are capable of being worked independently of each other, or in unison. Thus, for example, if only a limited supply of steam is required, the central generator only may be used, the wing furnaces of the other generator unit being damped down or out of action; while if a supply of steam is required that necessitates the use of the generators to their full capacity, the two boiler units can be in action simultaneously.

The invention will be further described with reference to the accompanying drawings, in which:—

Figure 1 is a front elevation (with one half in section) of a multitubular, three furnace marine-boiler, showing my invention applied thereto.

Figure 2 a longitudinal section of same.

Figure 3 is a half sectional front elevation of invention applied to a marine-boiler with four furnaces.

Referring to these figures, it will be seen that the central portion of the space enclosed by the ordinary boiler-shell 1 is divided off by the two longitudinal partitions 2 and the cross partition 3 to form a separate generator located centrally within the main boiler, which is thus divided into two independent generators, namely a central one 4, and an outer one 5 comprising the rest of the water and steam space within the main shell 1, and consisting mainly of two wing portions situated on the sides of the central generator.

The partition plates 2, which form the sides of the central generator, extend from top to bottom of the shell 1 and are riveted thereto. They are stayed together by lines of cross stay-bolts 6 pitched at suitable distances apart, with nuts 7 and 8 screwed on the bolts on opposite sides of the plates, and

with riveted washers 9 on the outer sides of the plates. In their lower part the partition plates 2 are suitably curved where they pass between the respective furnace tubes 10, 11, and 12 and are stayed to the wing furnace tubes 11 and 12 by stay-bolts 13 which screw into tapped holes in the plates and have nuts screwed therein at both sides, and are provided with riveted washers 14 at those places where the bolts pass through the plates in an angular direction. Still lower down, the plates 2 are stayed to the lower part of the boiler shell 1 by a line of expansion stays, each stay consisting of eyebolts 15, the threaded shanks of which are passed respectively through tapped holes in the shell 1 and the partition plates 2 and secured by nuts and washers, the eyebolts being coupled together by a link 16.

20 The back end of the generator 4 is formed by the flanged end-plate 3, which is riveted to the side plates 2 of the generator 4 and also at top and bottom to the boiler shell 1. It is also riveted to the rear flanged ends 25 17, 18, of the furnace tube 10, and to a frame 19. This frame 19 is angular in cross section and shaped to conform to the configuration of the front of the shell of the combustion chamber 20, to which it is riveted. The end-plate 30 3 also forms a back tube-plate for a nest of smoke tubes 21, which pass from the combustion-chamber 20 through the central generator 4 to a front tube-plate 22 and smoke-box (not shown) on the boiler front. The 35 front end of the central generator 4 is closed by the boiler front-end plate 23.

24 are the longitudinal stay-bolts of the main boiler shell, six of which are shown as passing through the central generator unit 4 and through its end-plate 3, these bolts being nutted on each side of the end-plate 3 and provided externally with riveted washers 25.

11 and 12 are the wing-furnaces for heating the generator unit formed by the rest of 45 the space within the main shell 1, and 26 and 27 are nests of smoke-tubes traversing the water space on each side of the central generator 4.

28 and 29 are manhole doors for giving access to the central generator 4.

Any suitable means may be provided for independently supplying the two generator units 4 and 5 with feed-water, and each of these generators is also fitted with other necessary fittings or mountings to enable it to be independently workable, such as stop-valves for drawing off steam, safety-valves, water and steam-pressure gauges, and so forth. 50 30 is a connection to a stop-valve for supplying high pressure steam from the central generator 4, and 31 the connection to the safety-valves of said generator. 32 and 33 are the connections to the corresponding valves of the other generator 5.

65 I declare that what I claim is:

1. A steam-generator having a plurality of generator units capable of being independently worked, comprising a common boiler shell formed as a horizontal cylindrical drum with closed ends; two vertical longitudinally-extending partitions in said drum, said partitions being of less length than the length of said drum; a transverse partition connecting said vertical partitions and separating the central space within the partitions from the remaining space in the drum, so that said remaining space forms a U-shaped unit, and the central space the central unit; stay-bolts connecting and spacing said partitions; and heating means and feed-water supply means in each of said generator units. 70 75 80

2. A steam generator as in claim 1, in which the central unit has a furnace tube which passes from the front wall of the drum to the transverse partition and seals furnace openings therethrough with respect to said central unit, and a furnace wall mounted on said transverse wall and forming a flue with the same in communication with said furnace tube, said wall sealing said flue from said U-shaped unit. 85 90

3. A steam generator as in claim 1, in which furnace openings are provided in the front wall of the drum, and flue openings are provided at the transverse partition, and furnace flues are located in the units and about said openings to seal the same, the vertical partitions passing between furnace flues of the central and the U-shaped unit, the flue for the generator unit extending to the said transverse partition and sealing the said flue opening therein and stay bolts connecting said vertical partitions with said furnace flues of the U-shaped unit. 95 100

4. In a steam generator, a common boiler shell, two longitudinal partitions reaching from top to bottom of said boiler shell and secured thereto, and extending from the front plate of the common shell and terminating at a distance from the rear wall thereof, a transverse partition having its edges connected to the said boiler shell and forming a back end plate connecting said longitudinal partitions to form central and wing units, said central unit being independently workable, walls forming in conjunction with said transverse partition a combustion chamber adjacent the rear wall of the common shell, and furnaces for said units connected between said transverse partition and said front plate, the front plate of said common shell being provided with firing openings for said furnaces, said furnaces communicating with said combustion chamber through openings in said transverse partition. 110 115 120 125

5. A steam generator as in claim 4, in which the said longitudinal partitions forming side walls of the central generator unit are stayed together by cross stays in their upper part, while in their lower part the said side walls 130

are stayed to the wing furnaces and also to the lower part of the main boiler shell.

6. A steam generator as in claim 4, in which said combustion chamber is extended upward 5 from the furnace openings in the said transverse partition, and fire tubes are provided above and parallel to the furnaces and extending between said front plate and said transverse partition.

10 In witness whereof, I have hereunto signed my name this 7th day of October, 1926.

MARK ROBINSON.
